UNITED STATES PATENT OFFICE.

GIACOMO PUCCI, OF WESTERLY, RHODE ISLAND.

STOP-MOTION MECHANISM FOR FLY FRAMES.

Application filed December 5, 1922. Serial No. 605,111.

To all whom it may concern:

Be it known that I, GIACOMO PUCCI, a citizen of the United States, residing at Westerly, in the county of Washington and State of Rhode Island, have invented certain new and useful Improvements in Stop-Motion Mechanism for Fly Frames, of which the following is a specification.

My invention relates to fly frames and comprises improvements in stop motions for fly frames which operate when the cone belt of the differential mechanism breaks. Whether the frame be bobbin lead or flier lead, great trouble has been experienced when the cone belt breaks. With a flier lead frame all the strands of roving on the frame are broken, and even in bobbin lead frames, the roving gets all tangled up around the fliers before the operator notices it, and a general snarling up and breaking of the roving takes place, which takes a long time to straighten out.

One object of my invention is to shut off the driving power by shifting the shipper rod and drive belt on breakage of the cone belt.

A further object of my invention is to quickly and effectually brake the movable parts of the machine, and stop the machine before the roving has a chance to get all snarled up.

A further object of my invention is to apply a double breaking mechanism, thereby doubly insuring the quick stopping of the movable parts, one element of my improved braking mechanism acting on the top cone shaft, and the other on the main drive shaft.

A further object of my invention is to provide an improved quick, even, resilient, braking means for braking machines of this sort.

A further object of my invention is to provide an improved trigger shaft release readily attachable to the already existing lower cone raising doffing means, and the lower cone support of any make of fly frame.

A further object of my invention is to generally improve upon devices of this nature by a provision of a strong, durable, efficient and inexpensive construction.

A further object of my invention is to eliminate the necessity of having two cone belts on machines of this type.

A further object of my invention is to

provide an improved automatic means for resetting stop motions of this type.

These and such other features of my invention as may hereinafter appear will be best understood from a description of one embodiment thereof, such as for instance, is shown in the accompanying drawings which illustrate an adaptation of my invention, to one type of fly frames.

In the drawings, Fig. 1, is a rear elevation of so much of the fly frame as is needed to illustrate my invention.

Fig. 2 is an end view of the same.

Fig. 3 is a fragmentary detailed view partially in section along the lines 3—3 of Fig. 1.

Fig. 4 is an end view of a fly frame, showing a modified form of braking means for controlling the main shaft.

Fig. 5 is a detailed view showing the means I employ for retaining the lower cone raising doffing mechanism in set position.

Fig. 6 is a detailed view showing the means I employ for varying the throw of the shipper rod.

In the drawings, wherein like characters of reference indicate like parts throughout, 1 is the frame of a fly frame. Spaced approximately equi-distantly with each other, and with the driving end frame support 2, along the fly frame are the supporting standards A', B', C', D', etc. These separate the frames into the sections A, B, C, D, etc., respectively. The section A (shown in Fig. 1, broken away) contains the differential mechanism for decreasing the speed of the bobbins, as they become more fully wound in bobbin lead frames, the section B contains the top and bottom cones of the differential mechanism and the lower cone raising means for doffing, the section C (shown in Fig. 1 broken away) contains the builder, traversing and cone belt shifting mechanisms, the section D, my improved trigger shaft shifting mechanism.

The upper cone 3, is driven by the main drive shaft 4, through a suitable train of gearing at a constant speed. The upper cone 3, drives by means of the cone belt 5, the lower cone 6. A mechanism in section C (not shown) causes the cone belt 5, to shift to the right as the bobbins get built up, and as the lower cone through a train of gear-

ing drives the differential mechanism in section A (not shown) at a gradually reduced speed, the bobbins are driven at a decreasing speed as they are built up. The weight 5 of the lower cone 6, which is normally made of metal usually rests on the cone belt 5. The lower cone 6, is supported by the lower cone support 7, fulcrumed on a connecting bar 8 of the frame 1. The reason that the 10 lower cone is pivotally supported is that it is desirable to raise the lower cone, and to run the ends slack for doffing purposes. The lower cone support is raised as follows, a lever 11, with a handle 12, is pivotally supported on an arm 13, extending 15 from the top plate 10 of the frame 1. The work arm 15, of this lever is provided with notches 14, for engagement with a pawl 16, mounted on the arm 13. When the handle 20 12 is shifted to raise the lower cone 6, the pawl 16, locks the lever 15, in raised position for doffing purposes. A lifting rod 17, is connected to the end of the work arm 15. This rod may be directly connected to the 25 lower cone support 7, to raise it for doffing purposes. However, I have provided means to allow the lower cone support 7, to drop sufficiently to trip the tripping lever 20, without disturbing the doffing mechanism. 30 For this purpose I have broken the lifting rod 17, and have pivoted it by means of the swinging arm 21 on a locking plate 22, attached to a convenient portion of the frame support B', directly above the lower 35 cone support 7. The swinging arm 21, is bent in a form of a partial U, the free end being pivotally connected to the lower end of the lifting rod 17. The swinging arm 21, has mounted thereon a pin 23, which 40 is adapted to register in a slot 24, in the locking plate 22. It is thus apparent that when the pawl 16, is out of engagement with the notches 14, on the under side of the work arm 15, of the lever 11, the sides 45 of the U of the swinging arm 21, will be retained by the registration of the pin 23 in the end of the slot 24 in an approximately vertical position. Pivoted to a point on the U shaped swinging arm 21 directly above 50 the lower end of the support 7, when the swinging arm 21 is in set position, is the auxiliary lifting rod 26. This is provided with a jack screw 27, for conveniently varying its length. The outer end of the lower 55 cone support 7, contains the vertical enclosed slot 28. The lower end of the auxiliary lifting rod 26, is provided with a pin 29, projecting at right angles therefrom for loose registration in the enclosed slot 28. The pin 29, projects through the slot 28, and is securely locked in place by means of the washer 30, and nut 31, on the opposite side of the lower cone support 7. It is thus apparent that when the lower 60 cone raising doffing mechanism is set into 65

position with the pin 23 in engagement with the slot 24, in the locking plate 22, the lower cone support is free to drop vertically the approximate length of the enclosed slot 28 on its outer end as the belt breaks. It is also apparent that the lower cone may be raised for doffing purposes as usual.

The tripping lever 20, is suitably fulcrumed on a rod 35, projecting from the frame support B'. The outer end of the lower cone support 7, is provided with the tripping extension 36, into which is threaded the tripping bolt 37. It is thus apparent that as the cone belt 6 stretches, proper adjustment may be made in the auxiliary lifting rod 26, and the tripping bolt 37. Immediately beneath the lower end of the tripping bolt 37, is the inner arm 38 of the tripping lever 20.

I employ means to effectually brake the upper cone shaft and the connected parts of the drive which I will now explain. On the upper cone shaft conveniently above the inner arm 38, of the tripping lever 20, I mount the pulley 41. Suitably fulcrumed on an extension 42, from the frame support B' is the brake lever 43. To the end of the short arm 44, of the brake lever 43, I attach one end of the brake band 45. The brake band 45, is a flat band preferably made out of resilient metal, although other material may be employed, and surrounds the face flange of the pulley 42, the other end thereof being attached to the long arm 46 of the brake lever 43. The brake rod 47, connects the ends of the long arm 46, of the brake lever 43, to the inner arm 38, of the tripping lever 20. It is thus apparent that as the inner arm 38, of the tripping lever 20, is tripped by the falling of the lower cone support 7, on the breakage of the belt, it will pull down the long arm 46 of the brake lever 43, and the end of the brake band 45, attached thereto, and push up the end of the brake band attached to the short arm 44 of the brake lever 43, thus clamping the brake band 45 around the pulley 41, and quickly braking and stopping the upper cone shaft. The brake band 45, is kept out of contact with the pulley 41 when not in use by means of the spring 48.

Suitably mounted in bearings on the driving end frame support 2, and the frame supports A', B' and C', is the trigger shaft 50. The outer arm 29, of the tripping lever 20, normally rests on the trigger shaft, and is retained thereon by the resilient pressure of the spring 40. Situated in sec. C, of the fly frame is the jack screw 51, for varying the length of the trigger shaft. Suitably fulcrumed on a frame extension in section D of the frame is a bell crank lever 52, the lower arm of which is attached to the trigger shaft 50. The upper arm of said lever is

connected by means of the rod 53 adjustable in length by means of the jack screw 54, to the power arm 55, of a lever 56, fulcrumed on a bracket 57, depending from the top 5 plate 10, of the frame. To the weight arm 58 of said lever are attached the weights 59. By varying the size of the weights 59, and by varying the adjustment of the rod 53 on the power arm 55, of the lever 56, it is obvious 10 that the thrust of the trigger shaft may be varied.

An extension 60, projects upwards from the lever 56. The shipper rod 61 is provided with a sleeve 62. Secured by means of the 15 nuts 63 in a vertical slot 64 in a downwardly projecting extension 65 of the sleeve 62, is the pin 66, adapted to be contacted by the extension 60 of the lever 56. It is obvious that as the weights 59 shift the lever 56, the 20 extension 60, bearing against the pin 66, will operate to throw the shipper rod 61 and belt 67 from the tight pulley 69, to the loose pulley 70. By varying the position of the pin 66 in the slot 64, it is obvious that the 25 throw of the rod may be varied so as to provide for variations in the size of the belt 7. Suitably secured to the trigger shaft 50, adjacent to the outer arm 39 of the tripping 30 lever 20, is the locking sleeve 73. The outer arm 39, of the tripping lever 20, normally bears laterally against the side 74 of the sleeve 73, and retains the trigger shaft 50, the lever 56, the weights 59 and shipper rod 61 in normal position. However, when the 35 belt 5 breaks, the lower cone support 7, drops sufficiently to lower the inner arm 38 of the tripping lever 20, and to raise the outer arm 39 of the tripping lever 20, above the sleeve 73. The weights 59 then forcibly shift the 40 trigger shaft 50 to the right, and as explained above, shut off the power by shifting the shipper rod 61 and drive belt 67. As previously explained, the lowering of the inner arm 38 of the tripping lever 20, simultaneously causes a breaking means to be applied 45 to the upper cone and its adjacent parts.

I also employ means to effectually brake the main drive shaft 4 of the fly frame. In 50 Figs. 1 and 2, I show a means that may be readily attached to any type of machine for breaking the balance wheel 75, with which most fly frames are already equipped. The supporting brackets 76 are suitably mounted 55 on the driving end frame support 2, and support the brake shaft 77. The brake shaft 77, is suitably linked by the downwardly projecting link 78, to the end of the trigger shaft 50. A bracket 80 is suitably attached 60 to the belt guard 81, and the brake lever 82 is pivoted thereon. The opposite end of the brake lever 82 is connected with the brake shaft 77, by the link rod 84 and arm 85. Mounted 65 on the upper surface of the brake lever 82 is the brake shoe 83, formed to

surround an arc of the outer surface of the balance wheel 75. It is obvious that on the sharp thrust of the trigger shaft 50 to the right (Fig. 1) the brake shaft 77 is sharply partially revolved and the brake shoe 83, is 70 forcibly pressed against the balance wheel 75, which is fast to the drive shaft 4, thus effectually braking the drive shaft and its connected parts.

In Fig. 4 is shown a modified form of 75 braking means which may be readily constructed on newly manufactured machines. I mount the pulley 86 on the main drive shaft 84 inside the balance wheel 75, and around the pulley I attach the novel type 80 of brake shown above for braking the upper cone. The brake lever 87, is suitably fulcrumed on an extension from the frame end support 2. The end of the long arm 88, of the brake lever, is suitably linked with the rod 89 and link 90 to the brake shaft 77. One end of the brake band 91, is attached 85 to the long arm 88 of the brake lever, the band itself is passed circumferentially around the pulley 86, and the other end is attached to the short arm 92 of the brake lever 90. The spring 93 prevents the brake band from contacting the pulley 86, when binding pressure is removed from the band 91. It is apparent that when a thrust is 95 exerted on the trigger shaft, downward pressure will be brought to bear on the long arm 88 of the brake lever, pulling down the end of the brake band attached thereto and pushing up the end of the brake band attached to the short arm 92 of the lever 87, causing circumferential pressure on the whole outer surface of the pulley 86, and effectually braking the drive shaft and its 100 connected parts.

In operation, when the cone belt 6 breaks, the lower cone support 7 drops sufficiently to trip the inner arm of the tripping lever 20, as explained in detail above. This causes the brake band 45 to break the upper cone drive shaft and its connected parts. As the outer arm 39, of the tripping lever 20, is raised free of the locking sleeve 73, the weights 59, through the connecting levers 56 and 52, cause the trigger shaft 50, to be sharply shifted to the right. As explained in detail above, the upwardly projecting extension 60, of the lever 56, moves the shipper rod 61 and shifts the belt 67 to the loose pulley, at the same instant that an effectual braking means is applied to the drive shaft of the frame as explained above.

To reset the stop motion; insert a new 125 belt of a desired length between the cones and lift up the weights 59; as all the parts are solidly connected by rods or levers, the locking sleeve 73 on the trigger shaft 50, will be automatically shifted to its proper 130 position adjacent to the outer arm 39, of the

tripping lever 20, and the springs 40 will force the outer arm 39 of the lever 20 into proper position to hold the trigger shaft 50 and weights 59, in set position, and automatically raise the inner arm 38 of the tripping lever 20, releasing the braking means on the upper cone, as the braking means are taken off the drive shaft. It is obvious that this automatic resetting is not possible where chains are employed. As the shipper rod is not directly connected to the weight, it is apparent that the frame may be started and stopped independently of the stop motion.

15 It is understood that the invention is not limited to the specific embodiment shown, and that various deviations may be made therefrom without departing from the spirit and scope of the appended claims.

20 What I claim as new and desire to secure as Letters Patent is:

1. In fly frames, the combination of the upper and lower cones of the differential mechanism, a cone belt, a lower cone support pivoted so as to drop on the breaking of the cone belt, a tripping lever adapted to be tripped by the pivoted cone support, and to release the trigger shaft on the breaking of the cone belt, braking means attached to one arm of the tripping lever adapted to brake the upper cone shaft, a trigger shaft, means adapted to forcibly shift the trigger shaft when released by the tripping lever, means connected to the trigger shaft adapted to shift the shipper rod on breakage of the cone belt, and a braking means attached to the driving end of the fly frame connected to the trigger shaft, and adapted on the forcible shifting of the trigger shaft to brake the drive shaft.

2. In fly frames, the combination of the upper and lower cones of the differential mechanism, a cone belt, a lower cone support pivoted so as to drop on the breaking of the cone belt, a tripping lever adapted to be tripped by the pivoted cone support, and to release the trigger shaft on the breakage of the cone belt, a trigger shaft, means adapted to forcibly shift the trigger shaft when released by the tripping lever, means connected to the trigger shaft adapted to shift the shipper rod on breakage of the cone belt, and a braking means attached to the driving end of the fly frame connected to the trigger shaft, and adapted on the forcible shifting of the trigger shaft to brake the drive shaft.

3. In fly frames, the combination of the upper and lower cones of the differential mechanism, a cone belt, a lower cone supporting means adapted to release the trigger shaft on breakage of the cone belt, a trigger shaft, means to forcibly shift the trigger shaft when released, and shipper rod shifting means, and driving shaft braking means,

both actuated by the forcible shifting of the trigger shaft.

4. In fly frames, the combination of the upper and lower cones of the differential mechanism, a cone belt, a lower cone support pivotally attached to the fly frame, a vertical enclosed slot in the outer end of said support adapted to receive a pin projecting from the depending rod of the lower cone raising dossal means, a lower cone raising dossal means, an adjustable arm on the end of the lower cone support adapted to trip the inner arm of the tripping lever, a locking plate to hold the lower cone raising dossal means in set position, a tripping lever fulcrumed on the fly frame, a pulley attached to the upper cone shaft, a lever fulcrumed on the frame near said pulley, a resilient brake band surrounding said pulley, one end thereof being attached to the short arm of said lever, the other end being attached to the long arm of said lever, a spring adapted to hold the brake band away from the pulley when not in use, a rod connecting the long arm of said lever to the inner arm of the tripping lever, a trigger shaft, a sleeve attached to the trigger shaft adapted to contact the outer arm of the tripping lever and to lock the trigger shaft, a spring adapted to retain the long arm of the tripping lever on the trigger shaft, a bell crank lever fulcrumed on the frame, the lower arm thereof being connected to one end of the trigger shaft, a lever fulcrumed on the top plate of the frame, the power arm thereof being connected by an adjustable rod to the upper arm of the bell crank lever, weights attached to the weight arm of said lever, an upwardly projecting extension from said lever adapted to engage an adjustable projection extending from a sleeve on the shipper rod, a shipper rod, a brake shaft suitably mounted on and extending laterally across the driving frame end support of the fly frame, a link connecting the end of the trigger shaft with the brake shaft, and braking means suitably linked to the brake shaft adapted to brake the main drive shaft.

5. In fly frames, the combination of the upper and lower cones of the differential mechanism, a cone belt, a lower cone support pivotally attached to the fly frame, a vertical enclosed slot in the outer end of said support, adapted to receive a pin projecting from the depending rod of the lower cone raising dossal means, a lower cone raising dossal means, an adjustable arm on the end of the lower cone support adapted to trip the inner arm of the tripping lever, a locking plate to hold the lower cone raising dossal means in set position, a tripping lever fulcrumed on the fly frame, a pulley attached to the upper cone shaft, a lever

fulcrumed on the frame near said pulley, a resilient brake band surrounding said pulley, one end thereof being attached to the short arm of said lever, the other end being attached to the long arm of said lever, a spring adapted to hold the brake band away from the pulley when not in use, a rod connecting the long arm of said lever to the inner arm of the tripping lever, a trigger shaft, a sleeve attached to the trigger shaft adapted to contact the outer arm of the tripping lever and to lock the trigger shaft, a bell crank lever fulcrumed on the frame the lower arm thereof being connected to one end of the trigger shaft, a lever fulcrumed on the top plate of the frame, the power arm thereof being connected by an adjustable rod to the upper arm of the bell crank lever, weights attached to the weight arm of said lever, an upwardly projecting extension from said lever adapted to engage an adjustable projection extending from a sleeve on the shipper rod, a shipper rod, a brake shaft suitably mounted on and extending laterally across the driving end frame support of the fly frame, a link connecting the end of the trigger shaft with the brake shaft, a pulley mounted on the main drive shaft, a brake lever fulcrumed on the end of the frame near said pulley, a resilient brake band surrounding said pulley, one end thereof being attached to the short arm of said lever, and the other end thereof to the long arm of said lever, a spring adapted to hold the brake band away from the pulley when not in use, an arm on the brake shaft underneath said lever, and a link rod connecting the long arm of said lever with said arm.

6. In fly frames, the combination of the upper and lower cones of the differential mechanism, a cone belt, a lower cone support pivotally attached to the fly frame, a vertical enclosed slot in the outer end of said support, adapted to receive a pin projecting from the depending rod of the lower cone raising dossal means, a lower cone raising dossal means, an adjustable arm on the end of the lower cone support adapted to trip the inner arm of the tripping lever, a locking plate to hold the lower cone raising dossal means in set position, a tripping lever fulcrumed on the fly frame, a trigger shaft, a sleeve attached to the trigger shaft adapted to contact the outer arm of the tripping lever and to lock the trigger shaft, and means to forcibly shift the trigger shaft when released by the tripping lever.

7. In fly frames, the combination of the upper and lower cones of the differential mechanism, a cone belt, a lower cone support pivotally attached to the fly frame, a vertical slot in the outer end of said support, adapted to receive a pin projecting from the depending rod of the lower cone raising dossal means, a lower cone raising dossal means, an adjustable arm on the end of the lower cone support adapted to trip the inner arm of the tripping lever, a locking plate to hold the lower cone raising dossal means in set position, a tripping lever fulcrumed on the fly frame, a trigger shaft, a sleeve attached to the trigger shaft adapted to contact the outer arm of the tripping lever and to lock the trigger shaft, and means to forcibly shift the trigger shaft when released by the tripping lever.

8. In fly frames, in combination, a trigger shaft, means to release said trigger shaft by the dropping of the lower cone on the breaking of the cone belt, a bell crank lever fulcrumed on the frame, the lower arm thereof being connected to one end of the trigger shaft, a lever fulcrumed in the top plate of the frame, the power arm thereof being connected by an adjustable rod to the upper arm of the bell crank lever, weights attached to the weight arm of said lever, an upwardly projecting extension from said lever adapted to engage an adjustable projection extending from a sleeve on the shipper rod, a shipper rod, a brake shaft suitably mounted on and extending laterally across the driving end frame support of the fly frame, a link connecting the end of the trigger shaft with the brake shaft, and braking means suitably linked to the brake shaft, adapted to brake the main drive shaft.

9. In fly frames, in combination, a trigger shaft, means to release said trigger shaft by the dropping of the lower cone on the breaking of the cone belt, a bell crank lever fulcrumed on the frame, the lower arm thereof being connected to one end of the trigger shaft, a lever fulcrumed on the top plate of the frame, the power arm thereof being connected by an adjustable rod to the upper arm of the bell crank lever, weights attached to the weight arm of said lever, an upwardly projecting extension from said lever adapted to engage an adjustable projection extending from a sleeve on the shipper rod, a shipper rod, a brake shaft suitably mounted on and extending laterally across the driving end frame support of the fly frame, a link connecting the end of the trigger shaft with the brake shaft, a pulley mounted on the main drive shaft, a brake lever fulcrumed on the end of the frame

ping lever and to lock the trigger shaft, and means to forcibly shift the trigger shaft when released by the tripping lever.

7. In fly frames, the combination of the upper and lower cones of the differential mechanism, a cone belt, a lower cone support pivotally attached to the fly frame, a vertical slot in the outer end of said support, adapted to receive a pin projecting from the depending rod of the lower cone raising dossal means, a lower cone raising dossal means, an adjustable arm on the end of the lower cone support adapted to trip the inner arm of the tripping lever, a locking plate to hold the lower cone raising dossal means in set position, a tripping lever fulcrumed on the fly frame, a trigger shaft, a sleeve attached to the trigger shaft adapted to contact the outer arm of the tripping lever and to lock the trigger shaft, and means to forcibly shift the trigger shaft when released by the tripping lever.

8. In fly frames, in combination, a trigger shaft, means to release said trigger shaft by the dropping of the lower cone on the breaking of the cone belt, a bell crank lever fulcrumed on the frame, the lower arm thereof being connected to one end of the trigger shaft, a lever fulcrumed in the top plate of the frame, the power arm thereof being connected by an adjustable rod to the upper arm of the bell crank lever, weights attached to the weight arm of said lever, an upwardly projecting extension from said lever adapted to engage an adjustable projection extending from a sleeve on the shipper rod, a shipper rod, a brake shaft suitably mounted on and extending laterally across the driving end frame support of the fly frame, a link connecting the end of the trigger shaft with the brake shaft, and braking means suitably linked to the brake shaft, adapted to brake the main drive shaft.

9. In fly frames, in combination, a trigger shaft, means to release said trigger shaft by the dropping of the lower cone on the breaking of the cone belt, a bell crank lever fulcrumed on the frame, the lower arm thereof being connected to one end of the trigger shaft, a lever fulcrumed on the top plate of the frame, the power arm thereof being connected by an adjustable rod to the upper arm of the bell crank lever, weights attached to the weight arm of said lever, an upwardly projecting extension from said lever adapted to engage an adjustable projection extending from a sleeve on the shipper rod, a shipper rod, a brake shaft suitably mounted on and extending laterally across the driving end frame support of the fly frame, a link connecting the end of the trigger shaft with the brake shaft, a pulley mounted on the main drive shaft, a brake lever fulcrumed on the end of the frame

near said pulley, a resilient brake band surrounding said pulley, one end thereof being attached to the short arm of said lever, and the other end thereof to the long arm 5 of said lever, a spring adapted to hold the brake band away from the pulley when not in use, an arm on the brake shaft underneath said lever, and a link rod connecting the long arm of said lever with said arm.

10 10. In stop motions for fly frames, which function on the breakage of the cone belt, in combination with means to shift the belt from a tight to a loose pulley on the main drive shaft on breakage of the cone belt, of 15 resilient braking means to brake the upper

cone shaft and resilient braking means to brake the main drive shaft on breakage of the cone belt.

11. In fly frames, in combination with the upper and lower cones of the differential 20 mechanism, a cone belt, a lower cone support pivoted to the frame, and a lower cone raising dossal mechanism, of means on the lower cone support adapted to co-operate with means on the lower cone raising dossal mechanism, to permit sufficient dropping of the lower cone support to actuate other mechanisms. 25

In testimony whereof I affix my signature.

GIACOMO PUCCI.
